UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,271,322.

Specification of Letters Patent.

Patented July 2, 1918.

Application filed April 24, 1917. Serial No. 164,172.

To all whom it may concern:

Be it known that I, CHARLES W. KECKLER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone 10 exchange systems, and more particularly to such systems of the central energy type, its object being to improve the service rendered by such systems.

In accordance with a feature of this invention, a link circuit employed for connecting together telephone lines terminating at a central office is provided with means for automatically connecting an operator's telephone set thereto upon connection of the link 20 circuit with a calling line. Preferably the means employed is an electromagnetic relay common to a plurality of link circuits.

In accordance with another feature of this invention, means are provided for the 25 link circuits by which it is impossible to connect the operator's telephone set to more than one link circuit at a time.

This invention is illustrated in the accompanying drawing in which all apparatus is 30 in its normal position with the operator's telephone set disconnected from the link circuits.

In the drawing there are shown two ordinary telephone lines A and B extending from 35 subscribers' stations and terminating at a central office where there are located a plurality of link circuits C and D for interconnecting the telephone lines. Only so much of the link circuits as is necessary for a 40 proper understanding of this invention is shown.

The connection of an operator's telephone set with the link circuit is controlled by a relay 5 common to the link circuits. This 45 relay 5 is in series with a polarized relay 6, across a Wheatstone bridge having three arms common to the link circuits, the fourth arm being provided in the separate link circuits. The arms common to the link circuits are 7, 8 and 9. The resistances of these 50 arms are so proportioned that, when none of the link circuits are in use, there is a flow of current from battery through the contact of key 11 to a point 12 where it divides, a 55 portion going through resistance arm 7 to a

point 13, and another portion going through resistance arm 8 and the windings of polarized relay 6 and relay 5 to the point 13 and thence through resistance arm 9 and ground. The polarized relay 6 is so poled that it does 60 not attract its armature when traversed by current flowing in the direction just traced. Relay 5, however, is operated, maintaining the operator's telephone set disconnected from the link circuits. When the answering 65 end of any link circuit, as C, is connected with a telephone line, the resistance 10—C is connected with the Wheatstone bridge and forms the fourth arm thereof. The bridge is now balanced and relay 5 releases its 70 armatures, connecting the operator's telephone set with the link circuit. Should the answering ends of two link circuits be connected with two telephone lines simultaneously, resistances 10—C and 10—D will be connected 75 in parallel to form the fourth arm of the bridge, and when so connected the bridge will be unbalanced. Relay 5, will, therefore, be operated, disconnecting the operator's telephone set from both link circuits. The 80 direction of flow of current through relays 5 and 6 will be such that polarized relay 6 attracts its armature causing the operation of a lamp 14, indicating to the operator that the answering ends of two link circuits have 85 been connected with two telephone lines, while the calling end of neither link circuit is engaged.

Operation: Assuming that the subscriber of telephone line A has initiated a call in 90 the usual manner, the operator in answering inserts answering plug 25 of the cord circuit C into line jack 26, whereupon answering sleeve relay 27 and cut-off relay 28 are operated. The operation of relay 27 connects answering supervisory relay 29 to the talking strands of the cord circuit, which is 95 thereupon operated to prevent the lighting of answering supervisory lamp 30. The operation of relay 27 also connects resistance 10 to the Wheatstone bridge, whereupon relay 5 releases its armatures, connecting the operator's telephone set to the talking strands of the cord circuit C. The operator, upon 100 being advised of the number of the line with which connection is desired, for example, line B, inserts calling plug 31 into a jack 32 associated with telephone line B. Calling sleeve relay 33 and cut-off relay 34 are thereupon operated. The subscriber of 105 110

telephone line B may be signaled in any well-known manner. The operation of relay 33 disconnects the common circuit leads 35 and 36 from the talking strands of cord 5 circuit C, and also disconnects resistance 10 from the Wheatstone bridge, thereby destroying the balance, and permitting the energization of relay 5. The energization of relay 5 disconnects the operator's telephone set from the common leads 35 and 36. The operation of relay 33 also connects calling supervisory relay 39 to the talking strands of cord circuit C, and causes the operation of calling supervisory lamp 40. 10 In response to the operation of the call bell at station B, the subscriber removes the receiver from the switchhook, thereby causing the operation of the calling supervisory relay 39 to extinguish the calling supervisory lamp 40. At the conclusion of the conversation the restoration of the receivers to the switchhooks causes the deenergization of the supervisory relays 29 and 39, whereupon the lamps 30 and 40 are lighted to furnish disconnect signals. The operator may now remove the plugs from the jacks, restoring all apparatus to normal. 15

Should the operator have inserted the answering plug 25 of cord circuit D into the jack of another calling line before the calling plug 31 of the cord circuit C was inserted into the jack 32 of line D, the resistance 10—D would be connected in parallel with the resistance 10—C, whereby the resistance of the fourth arm of the Wheatstone bridge circuit would be reduced, destroying the balance. Current would then flow from battery through the contact of key 11, bridge arm 7 and the windings of relays 5 and 6, and the bridge arm 8 in parallel therewith and the resistances 10—C and 10—D in parallel to ground. The current in this path operates relay 5, thereby disconnecting the operator's telephone set 20 from the common leads 35 and 36. Polarized relay 6 is also operated, causing the lighting of the lamp 14, which is a signal to the operator that the answering ends of two cord circuits have been connected with 25 two telephone lines, while the calling end of each of the cord circuits is not in use.

What is claimed is:

1. In a telephone exchange system comprising telephone lines, a plurality of cord circuits, an operator's telephone set, and a normally energized relay common to the cord circuits deenergized upon the connection of one end of one of the cord circuits with one telephone line to connect therewith the operator's telephone set and energized upon the connection of the other end of the cord circuit with another telephone line to disconnect the operator's telephone set.
- 65 2. A telephone exchange system comprising

telephone lines, a plurality of link circuits, an operator's telephone set, a Wheatstone bridge circuit having three arms common to the link circuits, means operating upon connection of one of the link circuits 70 with one of the telephone lines to complete the fourth arm of the bridge circuit, and a switching device in the bridge responsive to the completion of the fourth arm thereof to connect the operator's telephone set with the 75 engaged link circuit.

3. A telephone exchange system comprising telephone lines, a plurality of link circuits, an operator's telephone set, a Wheatstone bridge circuit common to the link circuits, means actuated upon connection of one of the link circuits with one of the lines to alter the electrical condition of the Wheatstone bridge circuit, and a switching device in the bridge responsive to the altered 85 condition thereof to connect the operator's telephone set with the engaged link circuit.

4. A telephone exchange system comprising telephone lines, a plurality of link circuits, an operator's telephone set, a Wheatstone bridge circuit having three arms common to the circuits, a resistance in each link circuit adapted to form the fourth arm of the bridge, a relay operating upon connection of one of the link circuits with one 95 of the telephone lines to connect the associated resistance with the bridge, and a relay in the bridge responsive to the connection of the resistance with the bridge to connect the operator's telephone set with the 100 engaged link circuit.

5. A telephone exchange system comprising telephone lines, a plurality of link circuits including talking conductors for interconnecting the lines, an operator's telephone 105 set, circuit leads common to the link circuits and normally connected to the talking conductors thereof, and means common to the link circuits for connecting the operator's telephone set to the common circuit leads.

6. A telephone exchange system comprising telephone lines, a plurality of link circuits including talking conductors for interconnecting the lines, an operator's telephone set, circuit leads common to the link 115 circuits and normally connected to the talking conductors thereof, and a relay common to the link circuits for connecting the operator's telephone set to the common circuit leads.

7. A telephone exchange system comprising telephone lines, a plurality of link circuits including talking conductors for interconnecting the lines, an operator's telephone set, circuit leads common to the link 125 circuits and normally connected to the talking conductors thereof, means common to the link circuits for connecting the operator's telephone set to the common circuit leads, and means associated with an en- 130

gaged link circuit for disconnecting the common circuit leads from the talking conductors thereof.

8. A telephone exchange system comprising telephone lines, a plurality of link circuits for interconnecting the lines, an operator's telephone set, circuit leads common to the link circuits and normally connected thereto, a relay common to the link circuits responsive to the connection of one end of one of the link circuits with a telephone line to connect the operator's telephone set with the common circuit leads, and a relay responsive to the connection of the other end of the engaged link circuit with another telephone line to disconnect the common circuit leads from the engaged link circuit.

9. A telephone exchange system comprising telephone lines, a plurality of link circuits, an operator's telephone set, a Wheatstone bridge circuit common to the link circuits, means actuated upon connection of one end of one of the link circuits with one of the telephone lines to alter the electrical condition of the Wheatstone bridge circuit, a switching device in the bridge responsive to the altered condition thereof to connect the operator's telephone set with the engaged link circuit, and means responsive to the connection of the other end of the engaged link circuit with another telephone line to restore the Wheatstone bridge circuit to normal condition to thereby disconnect the operator's telephone set from the engaged link circuit.

10. A telephone exchange system comprising telephone lines, a plurality of link circuits, an operator's telephone set, a Wheatstone bridge circuit having three arms common to the link circuits, a resistance in each link circuit adapted to form the fourth arm of the bridge, a relay operating upon connection of one of the link circuits with one of the telephone lines to connect the asso-

ciated resistance with the bridge, a relay in the bridge responsive to the connection of the resistance with the bridge to connect the operator's telephone set with the engaged link circuit, and a relay associated with the second link circuit operating upon connection thereof with a second telephone line to connect its associated resistance with the bridge and in parallel with the resistance of the first link circuit, the relay in the bridge being responsive to such connection to disconnect the operator's telephone set from the engaged link circuits.

11. A telephone exchange system comprising telephone lines, a plurality of link circuits, an operator's telephone set, a Wheatstone bridge circuit having three arms common to the link circuits, a fourth arm for the bridge connected therewith upon connection of one of the link circuits with one of the telephone lines, and a switching device in the bridge responsive to the connection of the fourth arm to the bridge to connect the operator's telephone set with the engaged link circuit.

12. A telephone exchange system comprising telephone lines, a plurality of link circuits, an operator's telephone set, a Wheatstone bridge circuit having three arms common to the link circuits, a fourth arm for the bridge connected therewith upon connection of one end of one of the link circuits with one of the telephone lines, a switching device in the bridge responsive to the connection of the fourth arm of the bridge to connect the operator's telephone set with the engaged link circuit, and means responsive to the connection of the other end of the engaged link circuit with another telephone line to disconnect the fourth arm from the bridge.

In witness whereof, I hereunto subscribe my name this 20th day of April, A. D. 1917.

CHARLES W. KECKLER.
